UNITED STATES PATENT OFFICE.

THOMAS MILLER, OF SEEKONK, MASSACHUSETTS, ASSIGNOR TO WARDWELL BRAIDING MACHINE COMPANY, OF PORTLAND, MAINE, A CORPORATION OF MAINE.

BRAIDING MACHINE.

Application filed August 3, 1923. Serial No. 655,538.

This invention consists in improvements in braiding machines and relates particularly to braiders of circular type in which the bobbins or yarn-supplies are arranged in opposite sets and revolved in concentric orbits about a common axis. In machines of this type the braiding operation is effected by deflecting the yarns from one set of supplies to cause them to follow a sinuous course over and under the supplies of the other set; instead of by bodily moving the bobbins or yarn-supplies in and out to pass them by each other.

One object of the present improvement is to provide a machine of the character specified in which the yarns are manipulated through their engagement with relatively fixed deflectors employed in place of the usual moving controllers or switches.

A particular object of the improvement is to provide a braider in which different patterns or "weaves" may be produced in the braid by a slight alteration in the arrangement of the parts of the machine, merely the substitution of one interchangeable deflector for another without dismantling the machine or disturbing its mechanism.

Further objects and advantages of the improvement are set forth in the following specification which describes a preferred embodiment of the invention as illustrated in the accompanying drawings. In the drawings:

Fig. 1 is a side elevation of my improved braiding machine showing its mechanism partly in section in a vertical plane taken through its axis;

Fig. 2, an enlarged detailed view of a portion of the yarn-manipulating devices of the machine, shown in connection with the traveling bobbin-carriers;

Fig. 3, a similar view showing the cooperating parts in a different relation;

Fig. 4, a diagrammatic plan view showing the arrangement of the two sets of bobbins or yarn-supplies, and illustrating their cooperative relation with respect to the yarn-manipulating devices or deflectors at a certain stage in the operation of braiding a particular pattern of braid;

Fig. 5, a similar view showing the relation of the same parts at a later stage in the braiding operation;

Fig. 6, a similar view showing the relation of the parts at a certain stage in their

operation where a modified arrangement of the manipulating-means is used to produce a different pattern in the braid;

Fig. 7, a similar view showing the relation of these same parts at a later stage 60 in the braiding operation;

Fig. 8, a similar diagrammatic plan view showing a portion of the yarn-supplies eliminated to adapt the machine to produce a braid comprising a less number of strands, 65 and illustrating the cooperating parts at a certain stage of the braiding operation;

Fig. 9, a similar view of this adaptation of the braiding-mechanism showing the parts in their relative position at a later 70 stage in the braiding operation; and

Figs. 10 and 11, still further diagrammatic views of this adaptation of the machine showing the parts at still later subsequent stages in the braiding operation. 75

Referring to Fig. 1 of the drawings, the present machine is similar in general respects to an improved braider invented by Simon W. Wardwell and illustrated and described in various U. S. Letters Patents 80 as follows: Patents No. 1,009,504, dated November 14, 1911; No. 1,032,870, dated July 16, 1912; No. 1,081,474, dated December 16, 1913; and No. 1,197,692 dated September 12, 1916. 85

The main operating-mechanism of the machine comprises, essentially, a base or standard 2 provided with a central, hollow, vertical post 3 and an overhanging bearing 4 for the drive-shaft 5. At the top of the standard 90 2 is a ball-race 6 for receiving a series of balls 7 on which the outer head or turret 10 rotates. The turret 10 is of substantially inverted cone-shape and is provided with a circular ball-race 11 arranged directly 95 over the main ball-bearing on the standard 2. A second, inner turret or head 12 is mounted to rotate on balls 13 in the race 11 and is provided with a central coniform cap or cover 14. 100

The outer turret or head 10 carries one set of bobbins or yarn-supplies X, mounted in spaced relation around its circumference, and is formed with a circular raceway or track 15 in which are slidably mounted a series of lenticularly-shaped carriers or shuttles 16 carrying the other set of yarn supplies Y. As shown in Fig. 1, the carriers 16 are provided with keels or runners which slide in the grooved track 15. 110

The outer turret 10 rotates about the axis of the machine in a clockwise direction, while the carriers 16 revolve in the opposite direction as propelled from the inner 5 turret 12.

The two turrets 10 and 12 are rotated in opposite directions by means of a bevel-pinion 17 fast on the inner end of the drive-shaft 5. The pinion 17 meshes with the teeth of a gear-ring 18 secured to the bottom flanged portion 19 of the turret 10; and the turret 12 is driven from a gear-ring 20 fastened to a depending sleeve 21 attached to the turret and enclosing the central post 3 15 of the frame 2. Power may be applied to the drive-shaft 5 through any suitable means such as the belt-pulley 22 arranged at the outer end of the bearing 4. Usually, the pulley 22 is connected to the drive-shaft 5 20 by means of a clutch-mechanism which is not herein shown since it may be of any suitable construction as generally employed for like purposes.

The inner turret 12 is connected to propel the carriers or shuttles 16 around the track 15 by means of pairs of reciprocating driver-bars 25. The driver-bars 25 slide in inclined slots on the inner conical face of the turret 12 and carry studs or rollers 26 on their under sides which engage with the groove 27 of a cam 28. The cam 28 is formed as a part of, or attached to, the outer turret 10, and as the two turrets rotate in opposite directions the undulatory form of the cam-groove 27 effects a rapid reciprocatory motion of the driver-bars 25. Two driver-bars are provided for each carrier 16 and their arrangement is such with relation to the cam 28 that one bar will be engaged with its respective carrier while the opposite bar of this pair is disengaged therefrom. The purpose of this arrangement, which is commonly used in braiders of this type, is to provide that the carriers will be at all times connected with their propelling-means, while also adapting the driver-bars to oscillate to permit the passage of the strands or yarns between the carriers and the propelling-head or turret. That is to say, as the yarns or strands α from the outer bobbins or supplies X are passed under the yarns γ from the inner supplies Y, the respective driver-bars for each carrier or shuttle will be alternately withdrawn and engaged again with the carrier to allow the passage of the strands along the inner edge of the carrier. The arrangement of this part of the mechanism is not herein shown in detail and requires no further explanation since it is illustrated in the 50 patents above referred to and is well known to those versed in the art. Suffice it to state that the track or raceway 15 for the carriers 16 is formed in an overhanging rim 29 on the outer turret 10 and this rim is divided into arcuate sections, see Figs. 2 and 3,

whereby a series of spaces or openings 30 are provided in which the yarns play back and forth to pass them to one side or the other of the shuttles or carriers 16 sliding through the track-sections.

70

The yarn-supplies X of the outer set are carried on brackets 32 fixedly attached to the rim 29 of the outer turret 10. Suitable tension-means or let-off devices 33 are provided on each bracket 32 for controlling the 75 unwinding of the yarn α from the bobbin or supply-cop X. Similar let-off devices are applied to the shuttles or carriers 16 to control the delivery of the yarns γ from the bobbins Y, but since such devices are well known and commonly used in the present art they are not herein shown or described in detail.

80

The construction of the braiding-mechanism so far described is substantially the 85 same as that illustrated in the patents previously referred to and my present improvement comprises, as before stated, a novel and ingenious arrangement of the mechanism for manipulating the yarns to cause their interlacing to produce different patterns in the 90 braid.

95

In the machines of the patents herein referred to, and in other machines of the same type, the yarns from the outer set of supplies are guided in a mean circular path or orbit, and are deflected from this normal course at certain definite intervals to pass them over and under the carriers of the other set of supplies. The means for guiding the yarns in their normal path may consist of V-shaped, crotch-like elements 35 which are formed of wire and held in extensions 36 of the brackets 32, as shown in Figs. 2 and 3 of the present drawings. The 105 yarns α from the bobbins X pass from their tension devices through the crotches 37 of the guides 35, and are maintained therein by the tension on the strands as they draw to the braiding point b to merge in the 110 fabric B, as shown in Fig. 1. Conveniently, the guides 35 are arranged to direct the yarns α in a path which will cause them to engage with the inner edges of the pointed 115 prows of the shuttles 16 when they meet the shuttles as the latter travel in the opposite direction from that of the yarns. It is obvious that with such an arrangement all of the yarns α from the bobbins X of the outer set would normally pass under all of 120 the yarns γ from the inner bobbins Y so that no braiding action would take place. In order, however, to cause the yarns α to pass above some of the yarns γ , to effect 125 the over and under braiding action, it has heretofore been the usual practice to provide movable switches operating in conjunction with the leading points of the shuttles 16 to deflect the yarns α onto the outer edges of said shuttles. That is to say, as the yarns 130

α from the outer set of supplies X come into juxtaposition with the leading ends or prows of the shuttles 16, the movable switches act to deflect these yarns onto the outer edges of the shuttles 16 whenever it is desired to pass said yarns over instead of under the yarns γ . The switches are operated intermittently with their movement timed to cause a certain predetermined manipulation of the yarns. In some cases the switches will be in "open" position, whereby the yarns traveling in their normal course will be allowed to meet the inner edges of the shuttles 16 so that they are deflected inwardly to pass them under the yarns γ ; while in other cases the switches will be "closed" to shift the yarns outwardly onto the outer edges of the shuttles 16 whereby they will ride up over said shuttles to pass them above the yarns γ leading from the bobbins Y. As the yarns are thus deflected to one side or the other of the shuttles 16 the curved or lenticularly-shaped edges of the decks of the shuttles act with a further deflecting effect to guide the yarns past the bobbins Y carried on the shuttles so that there will be no interference with their passage thereover or thereunder. As the yarns α ride along the curved edges of the shuttles 16 they will play either outwardly or inwardly along the branches 38 and 39 of the guides 35, but after each yarn has been passed over or under the high point on the edge of the shuttle it will again be drawn back into the crotch of the guide 35 so that normally its course will be defined in a mean circular path to cause it to meet the leading end of the next shuttle of the series in proper relation thereto.

Various types of oscillating and reciprocating switches have heretofore been employed to deflect the yarns as they meet the pointed prows of the shuttles, but in the present invention an important feature of improvement consists in eliminating all such movable yarn-deflecting means or switches. That is to say, in the present invention it is proposed to employ a fixed switch or, more properly, a fixed deflector which requires no intermittent movement or oscillation to effect the manipulation of the yarns to define their path of movement over and under the bobbins carried by the shuttles.

As herein shown, the fixed switch or deflector takes the form of a substantially T-shaped element or arm 40 reaching upwardly from the base 2 of the machine, see Figs. 1 and 2, and provided with an upper horizontal cross-bar 41. The arms 40 are preferably mounted on an outwardly-projecting annular rim 42 on the base 2, and are provided with feet 43 fastened to the rim by means of screws 44. The arms 40 are bent at 45 and reach outwardly and upwardly beneath the overhanging brackets 32 which are fastened to the rim of the outer turret 10 at 46. The cross-bar or T-head 41 of each arm 40 is thus brought into close relation with the outer periphery of the track-sections 29, see Figs. 2 and 3, and usually this part of the arm is made arcuate to conform to the circular contour of the track-sections. At the righthand end of the cross-bar 41 is a downwardly extending inclined guard-piece 48 designed to lift the yarns as they come into contact therewith to cause them to ride up onto the top of the cross-bar 41.

It is to be understood that braiding machines of the present type may comprise any desired number of bobbins, usually an even number, such as four, six, eight, twelve, sixteen, or multiples thereof in one set, and an equal number in the other set. In my present invention I may employ in some instances a number of fixed switches or deflectors equal to the number of bobbins in each set; while in other cases there may be one deflector for each two bobbins of either set, or any other combination may be employed in accordance with the character or pattern of the braid to be produced. Likewise, I may form the deflectors with guiding-arms or cross-bars 41 of different lengths, whereby they will have a variable cooperative relation with respect to the shuttles for the inner set of supplies to thus act with different deflecting effects on the yarn α in defining their path of travel over and under the yarns γ from the inner supplies. In this manner the present improved deflector may be employed in different forms to regulate the order of intermeshing the yarns to produce different patterns in the braid, and by simply removing one set of deflectors and substituting another set of a different type a variety of patterns may be incorporated in the braid produced on the one machine.

In the present drawings Fig. 2 illustrates at the left how the yarn α from the outer bobbin X is normally directed by the crotch of the guide 35 in a course which will cause it to pass under the pointed end of the shuttle 16 as the latter meets the yarn in passing from one track section 29 to another; while at the right of this view the next yarn α is shown as having met the inclined end or guard-piece 48 of the deflector 40 and been lifted thereby onto the upper edge of the cross-bar 41, so that said yarn is raised to a position in which it will meet the outer edge of the carrier 16, rather than its inner edge, to cause it to be passed above the yarn γ from the bobbin Y carried on said shuttle. Fig. 3 shows this second yarn α as having passed along the guiding edge of the cross-bar 41 until it has met the pointed end of the next traveling shuttle 16 and been caused to engage with the outer edge of this shuttle, this action causing this

yarn x to be passed above two yarns y of the inner set of supplies Y . The next or third yarn x is shown at the right in Fig. 3 as being passed under the inner edge of the first shuttle 16, but this yarn will next be passed over the bobbin Y on the next succeeding shuttle 16. The method of operation of this form of deflector during the complete braiding operation will be more clearly understood from the following explanation taken in connection with the diagrammatic views, Figs. 4 and 5.

In Figs. 4 and 5 the outer yarns are designated x' , x^2 , x^3 , etc., and the inner yarns y' , y^2 , y^3 , etc., to more clearly indicate the order of passing the yarns over and under each other as illustrated by these two views. The machine illustrated in these diagrams employs six shuttles carrying the inner supply-bobbins Y , and a like number of outer bobbins X from which the yarns x deliver. Only three fixed deflectors or yarn manipulators 40 are used with this combination and the resulting effect is as follows: In Fig. 4 the yarn x' is shown as being free from the influence of the deflectors 40, and it is therefore caused to pass under the yarn y' of the inner set. The next yarn x^2 , however, is being deflected and held raised out of its normal course by one of the deflectors 40 and it is therefore caused to pass over the next inner yarn y^2 . The next outer yarn x^3 is free from the influence of the deflectors and so will pass under the next inner yarn y^3 , while the next yarn x^4 rides on the deflector 40 to pass it over the next inner yarn y^4 , this same order being observed completely around the machine. It will be noted from Figs. 4 and 5 that the deflectors or manipulating-devices 40 have relatively long guiding-surfaces and these act to control each outer yarn x to pass it over two of the shuttles 16 carrying the supplies Y .

Referring now to Fig. 5 it will be seen that the yarn x' after passing under the yarn y' will also pass under the yarn y^6 leading from the supply Y on the next shuttle 16, since it remains free from the influence of the controllers 40 when it meets the prow of this shuttle. Likewise, the yarn x^2 which has been passed over the yarn y^2 , as shown in Fig. 4, will also be continued in its raised course through its engagement with the deflector 40 to pass it over the next yarn y' . In this way each outer yarn x is caused to pass first under two of the inner yarns y and then over two of them, or in other words, each of the yarns from one set of supplies passes alternately over and under the yarns from the other set in pairs to produce a particular pattern in the braid.

In Figs. 6 and 7 the machine is shown with the same number of inner and outer supply-bobbins, that is six in each set, but the yarn-manipulators or deflectors 40 are

illustrated as having cross-bars or guiding edges of less length, substantially half the length of those of the deflectors shown in Figs. 4 and 5. With this modification of the invention the yarns x from the outer set of supplies will be passed over and under the yarns from the inner set singly in alternate order. This order of passing the yarns x over and under the yarns y will be clearly understood by reference to these two views, 75 in which the yarns are designated by the same reference characters as in Figs. 4 and 5. As shown in Fig. 6 all of the yarns x' , x^2 , x^3 , etc., are shown engaged with the deflectors 40, there being six of these devices 80 in use, instead of the three employed with the arrangement previously described. Each deflector 40 has a shorter guiding-edge, however, and the result is that all of the yarns x will first be passed above the inner yarns 85 y as shown in Fig. 6, and then passed under the next succeeding inner yarns y as shown in Fig. 7. In other words, the yarn x' passes over the yarn y' , then under the yarn y^6 , while the yarn x^2 passes over the 90 yarn y^2 and then under the yarn y' , and so on throughout the series to produce a pattern having a regular over and under crossing of the single strands in alternate order.

Figs. 8, 9, 10 and 11 illustrate how the operation of the machine may be further modified by removing some of the supplies to produce a braid from a less number of strands and with different patterns incorporated therein. In these views the bobbins Y are missing from two of the shuttles 16, and two of the outer bobbins X are also eliminated so that there are four yarns x in the outer set and four yarns y in the inner set. In the arrangement here shown four deflectors 40 are employed having the longer guiding-surfaces or cross-bars 41, and the resulting effect on the braiding operation is as follows:

In Fig. 8 the yarns x' , x^2 , x^3 and x^4 from the outer supplies X are shown as raised or diverted from their normal course by the deflectors 40 to cause them to pass to the outside of the shuttles 16 carrying the supplies Y , and hence these yarns will all be caused to pass respectively above the several yarns y' , y^2 , y^3 and y^4 . At the next stage in the operation of the machine, as illustrated in Fig. 9, the first yarn x' will still be supported by the deflector 40 so that it will pass to the outside of the next succeeding shuttle which it meets, but as this shuttle carries no supply its conjunction with the passing yarn will have no effect on the pattern of the braid. The second yarn x^2 at this juncture 120 will have traveled beyond the control of the deflector 40, and having returned to its normal course will be led to the inside of the shuttle for the yarn y' so that it will pass under this yarn. The third yarn x^3 , mean- 125

while, will pass to the outside of the next shuttle 16, due to its continued engagement with the deflector 40, but there being no supply on this shuttle the effect on the pattern of the braid will be nil. On the other hand, the fourth yarn x^4 being free from the influence of the deflectors will pass to the inside of the next shuttle and hence under the yarn y^3 .

10 Referring now to Fig. 10, at the next stage in the cycle the yarn x' will be free from the control of the deflectors and will therefore pass under the yarn y^4 while the next yarn x^2 is passing to the outside of the first empty shuttle 16; the yarn x^3 being also free from the influence of the deflectors will pass under the yarn y^2 and the yarn x^4 will pass to the outside of the second empty shuttle. At the next stage, illustrated in Fig. 11, the yarn x' will be diverted once more by one of the deflectors 40 to pass it to the outside of the shuttle carrying the supply Y for the yarn y^3 and hence it will pass above this yarn. The yarn x^2 will also be influenced by a deflector to pass it above the yarn y^4 , and likewise the yarns x^3 and x^4 will be deflected to pass them respectively above the yarns y' and y^2 .

15 It will thus be seen that with the above described relation of the parts of the machine their cooperative action is such that each of the outer yarns x will be manipulated to sinuate it through the yarns y of the inner set with an alternate over and under braiding action, the first yarn x' passing first over one yarn y' , then under the next yarn y^4 , then over the yarn y^3 and under the yarn y^2 ; while the next yarn x^2 will interlace singly with these same yarns in opposite order, that is, first under the yarn y' then over the yarn y^4 , and so on to complete the cycle.

20 Other combinations may be arranged as regards the number of bobbins employed and the number and type of deflectors used therewith, whereby to produce still different effects in the pattern of the braid, and in this way my improved machine has a wide amplitude of adaptability for braiding various kinds of fabric with the yarns enmeshing in accordance with a variety of patterns.

25 To alter the braider to modify its method of manipulating the yarns, whereby the character of the pattern in the braid is changed, requires only the rearrangement of the parts of the machine or the substitution of one set of parts for another. In brief, to change the pattern of the braid produced on the machine requires only the removing of one set of deflectors and the substitution of another set, this alteration being accomplished very quickly without disturbing the main parts of the braider. The main operating-mechanism of the machine is never altered or interfered with and no adjustment of the operating parts is required as is the

case with machines having movable switches which are timed for definite periods of operation. In changing the deflectors 40 it is only necessary to remove their screws, and since the deflectors are positioned around the outside of the braider this can be accomplished very quickly and conveniently without dismantling or disturbing any of the parts of the braiding-mechanism and without rearranging or rethreading the supply-yarns themselves.

30 Without limiting myself to the precise construction of the invention as herein shown and described, I claim:—

1. In a braiding machine, the combination of a base, a turret having circular track-sections rotatable above the base, shuttles travelable on the track-sections to revolve a set of yarn-supplies about the axis of the machine, a second set of supplies carried on the turret to revolve in the opposite direction from that of the shuttles, and deflectors mounted on the base and projecting upwardly therefrom with elongated yarn-guiding portions at their upper ends extending substantially parallel with and arranged in close proximity to the track-sections and adapted to be engaged by the yarns from the second set of supplies to divert said yarns from their normal course to pass them above the shuttles.

2. In a braiding machine, the combination of a base, a rotating turret having an outer sectional track, carriers travelable on the track to revolve a set of yarn-supplies about the axis of the machine, means to propel the carriers around the track, a second set of yarn-supplies revolved by the turret in the opposite direction from that of the carriers, and deflectors supported from the base and each having an upright arm with a cross-bar at the top arranged adjacent the track-sections and adapted to engage the yarns from one set of supplies to divert them from their normal course to cause them to pass above the shuttles.

3. In a braiding machine, the combination of a standard, a turret rotatable on the standard, a set of yarn-supplies carried on and revolved by the turret, a circular track on the turret, shuttles travelable on the track, means to propel the shuttles around the track in a direction opposite to the direction of rotation of the turret, and deflectors supported from the base of the standard and having elongated guiding surfaces conforming to the contour and arranged in proximity to the circumference of the track to adapt them to be engaged by the yarns from the supplies carried on the turret to divert said yarns from their normal course to raise them above the leading ends of the shuttles whereby they pass above the yarns from the supplies carried on said shuttles.

4. In a braiding machine, the combina-

- tion of a base, a turret rotatable on the base, overhanging brackets depending from the rim of the turret, yarn-supplies carried by said brackets, a circular track on the 5 turret, shuttles travelable on the track and carrying a second set of yarn-supplies, means to propel the shuttles around the track in a direction opposite to the direction of rotation of the turret, yarn-guides on the 10 turret having means engaging the yarns from the supplies carried by the turret to normally restrain said yarns from lateral movement to direct them in a definite course to pass them to one side of the shuttles, and 15 deflectors mounted on the base and provided with horizontally-disposed guiding-faces arranged concentric with the track in close proximity thereto and adapted to deflect the guided yarns out of their normal course to 20 pass them by a predetermined number of shuttles on the opposite side from that on which they would normally pass.
5. In a braiding machine, the combination of a base, a turret rotatable on the base, 25 a circular track on the rim of the turret, shuttles travelable on the track and carrying a set of yarn-supplies, means to propel the shuttles around the track in a direction opposite to the direction of rotation of 30 the turret, brackets depending from the track and carrying a second set of yarn-supplies, and T-shaped deflectors supported at their lower ends on the base and extending upwardly beneath the brackets with their 35 upper elongated cross-bars arranged concentric with the track and disposed in close proximity thereto to adapt them to deflect the yarns from the second set of supplies to cause them to be passed above the leading ends of the shuttles traveling on the 40 track.
6. In a braiding machine, the combination of a base, a turret rotatable on the base, a circular track on the rim of the turret, shuttles travelable on the track and carrying 45 yarn-supplies, means to propel the shuttles around the track, brackets mounted on the turret and carrying a second set of yarn-supplies, and interchangeable deflectors each having a foot adapted to be secured to the 50 base and provided with a standard extending upwardly therefrom with a horizontally disposed lateral arm at the top arranged concentric with the track in close proximity thereto to deflect the yarns from the second 55 set of supplies to divert them from their normal course to pass them above the leading ends of the shuttles traveling on the track.
7. In a braiding machine, the combination 60 of a base, a turret rotatable on the base and provided with a circular track, shuttles travelable on the track to carry and revolve a set of yarn-supplies about the axis of the machine, means on the turret for supporting a second set of supplies to revolve them in the opposite direction from that of the supplies on the shuttles, deflectors mounted on the base and projecting upwardly therefrom with elongated yarn-engaging portions 65 arranged concentric with and disposed in close proximity to the track, and yarn-guides on the turret having divergent arms along which the yarns from the second set 70 of supplies slide and crotch-portions in which said yarns are normally restrained from lateral movement to direct them in a mean orbital path until they are engaged by the deflectors to shift them along the 75 arms of the guides to pass them to one side of the shuttles.

In testimony whereof I affix my signature.

THOMAS MILLER.
